(57) **CLAIM**

The ornamental design for a breast pump, as shown and described.

DESCRIPTION

FIG. 1 is a top perspective view of a breast pump with a handle in a down position;

FIG. 2 is a front elevation view of the breast pump with the handle in the down position;

FIG. 3 is a rear elevation view of the breast pump with the handle in the down position;

FIG. 4 is a top plan view of the breast pump with the handle in the down position;

FIG. 5 is a bottom plan view of the breast pump with the handle in the down position;

FIG. 6 is a left side elevation view of the breast pump with the handle in the down position;

FIG. 7 is a right side elevation view of the breast pump with the handle in the down position;

FIG. 8 is a top perspective of the breast pump with the handle in a raised position;

FIG. 9 is a front elevation view of the breast pump with the handle in the raised position;

FIG. 10 is a rear elevation view of the breast pump with the handle in the raised position;

FIG. 11 is a top plan view of the breast pump with the handle in the raised position;

FIG. 12 is a bottom plan view of the breast pump with the handle in the raised position;

FIG. 13 is a left side elevation view of the breast pump with the handle in the raised position; and,

FIG. 14 is a right side elevation view of the breast pump with the handle in the raised position.

Evenly spaced broken lines represent portions of the breast pump that form no part of the claimed design.

1 Claim, 14 Drawing Sheets
